UNITED STATES PATENT OFFICE.

GEORGE G. MITCHELL, OF UNION, NEW JERSEY, ASSIGNOR TO L. A. SAYRE COMPANY,
A CORPORATION OF NEW JERSEY.

FENCE-MAKER'S TOOL.

Application filed March 23, 1921. Serial No. 454,726.

To all whom it may concern:

Be it known that I, GEORGE G. MITCHELL, a citizen of the United States, and a resident of the town of Union, in the county of

5 Union and State of New Jersey, have invented new and useful Improvements in Fence-Makers' Tools, of which the following is a specification.

This invention relates to a tool for use in 10 the construction and repair of wire fences adapted to be utilized as a hammer for driving staples or nails, a staple or nail extractor, a wire stretcher, and a wire cutter.

The objects of the invention are to provide 15 a device of the character described comprising a pair of similar members pivotally connected intermediate their ends each having at one end a jaw adapted to cooperate with the corresponding end of the 20 other member to withdraw staples, nails and the like, said jaws being formed with transverse curved knife edges to penetrate the material around a staple the head of which is flush with the surface of the material and 25 cut away said material adjacent the staple to enable the jaws to grip the staple for extraction thereof; to provide jaws which when closed form a head with its opposite sides in substantially parallel planes and its 30 front end rounded longitudinally of the edge thereof for its entire length and curved transversely of said edge from one of said planes to the other, the faces of said jaws being oppositely recessed to provide walls 35 which are substantially straight transversely of the head and which curve from the extreme ends of the jaws substantially to the parallel sides of the head; to thus secure jaws with adjacent gripping portions 40 which have roundedly pointed cutters of substantially the thickness of the jaws and with cutting edges which are continuous from side to side of the tool and to obtain other results and advantages as may be 45 brought out by the following description.

Referring to the accompanying drawings, in which like numerals of reference indicate the same parts throughout the several views,

50 Figure 1 is a front elevation of a fence making and repairing tool constructed in accordance with my invention;

Fig. 2 is a side elevation thereof;

Fig. 3 is a front elevation of the jaw end 55 of the tool, showing the manner of using the same for extracting a staple or a nail;

Fig. 4 is a fragmentary perspective view of one of the jaws; and

Fig. 5 is an end elevation of the jaw end of the tool.

In the embodiment of my invention shown 60 on the drawings, the reference characters A designate opposed members duplicate in form pivotally connected intermediate their ends as at 1, one end of each of which comprises a handle portion 2. The opposite ends 65 of said members A are formed with enlarged jaws 3 arranged at substantially right angles to the respective handle portions 2 and terminating at their outer sides in hammer faces 4. The adjacent faces of the jaws 3 70 are cut away divergently inward from the outer ends thereof to form transverse knife edges 5 for the purpose of extracting a staple or nail from an object into which it is driven. A pocket 6 is thus formed between the knife edges 5, and it will be seen that the knife edges are movable toward and from each other by oscillation of the handle portions 2. The knife edges 5 are 75 suitably hardened to withstand contact with staples and nails, and are formed at their inner ends with projections 7 which abut when the jaws are brought together to maintain the outer ends of the knife edges in spaced relation to prevent injury thereof 80 by contact with each other.

The outer ends of the jaws 3 are transversely curved and formed with longitudinally extending continuous curved cam bearing surfaces 8 which recede from the respective knife edges 5, as shown in Figs. 2 90 and 4. With this construction it will be seen that with the knife edges 5 swung apart from each other they will readily penetrate an object as indicated at C, in which a 95

staple B or nail to be withdrawn is positioned, the knife edges being forced into the object on opposite sides of the staple or head of the nail. To withdraw the staple or nail it is then merely necessary first to 100 force the handle portions 2 toward each other to cause the jaws 3 to close upon the staple or nail head. The knife edges 5 cut away the material of the object on both sides of the staple or nail and grip the staple or 105 nail head between them, as clearly shown in Fig. 3 of the drawings. The bearing surfaces 8 then rest snugly against the face of the object, and lateral pressure applied upon the handle portions in the plane of the tool 110

in either direction will cause the corresponding bearing surface 8 to roll over the said surface of the object as shown by dot-and-dash lines in Fig. 3. The bearing surface 8 thus forms a fulcrum for the tool which serves as a lever, and it will be observed that the contact point of the bearing surface with the surface of the object in the initial movement of the extracting operation is positioned closely adjacent the head of the staple or nail so that the maximum leverage is obtained at the initial movement of the extracting operation when the most power is required.

15 The sharply transversely curved knife edges 5 can be quickly and deeply embedded into the object adjacent the staple or nail to be withdrawn, and the knife edges diverging inwardly act with a shearing operation on the material so as to cut away the same from opposite sides of the staple or nail head. The curved bearing surfaces 8 operate as fulcrums with a smoothly rolling action so as to provide a constantly moving 25 fulcrum point which renders the withdrawing of a staple or nail a simple and easy operation.

The pivotal portions of the members A are enlarged as at 9 and halved together, 30 the said portions of the respective members A being provided in the edges thereof with transverse slots 10, the said slot of one of the members cooperating with the corresponding slot of the other member to 35 serve as a wire cutter. The engaging and cooperating edges 11 of said slots are formed with knife edges which are acutely angular in cross-section, the said edges being formed by inclining the corresponding sides 12 of the slots 10 outwardly from the said edges 11. The knife edges 11 will thus keenly and quickly cut wire or 40 the like, the inclined sides 12 of the slots producing a true shearing action of the said knife edges.

The projections 7 of the jaws 3 in addition to serving as stops for preventing contact of the knife edges 5 also serve as pliers, and inwardly of said surfaces the jaws are 45 formed with recesses 13 which cooperate for wire twisting operations. The inner ends of the handle portions 2 are also formed with cooperating toothed portions 14 for use in wire twisting and stretching operations.

50 By my improved construction of jaws 8, 8, I secure when said jaws are closed a head with its opposite sides in substantially parallel planes and its front end rounded longitudinally of the edge thereof for its 55 entire length and curved transversely of said edge from one of said planes to the other, the faces of said jaws being opposite-

ly recessed to provide walls which are substantially straight transversely of the head and which curve from the extreme ends of the jaws substantially to the parallel sides of the head; the gripping portions of the jaws thus have roundedly pointed cutters of substantially the thickness of the jaws and the cutting edges are continuous from side 60 to side of the head of the tool. Said cutting edges therefore cut into the wood on both sides of a staple sunk flush with the surface of a post, oblique to the grain of the wood, and furthermore the cutters constructed as 65 pointed out have the requisite strength for said cutting edge to stand up under hard and rough usage in the way described. A very durable and efficient tool is thus secured by my improvements.

Having thus described the invention, what I claim is:

1. A tool of the character described having a head formed of two jaws movable toward and from each other and formed with 70 opposed cooperating faces, the outer ends of said jaws being similar and longitudinally curved recedingly from said opposed faces thereof and transversely curved from side to side throughout their lengths so that the 75 jaws are of substantially uniform thickness throughout their lengths, the said opposed faces of said jaws being oppositely recessed divergingly inward from the outer ends thereof, and said recessed portions extending from side to side of said jaw to form roundly pointed cutters of substantially the 80 thickness of the jaws which are continuous throughout the transverse curvature of the outer ends of the respective jaws, whereby 85 each of said jaws is provided with a rugged penetrating point having curved cutting edges.

2. A tool of the character described having a head formed of two jaws movable toward and from each other and having opposed cooperating faces, opposite sides of said head being disposed in parallel planes and the outer ends of said jaws being similar and transversely curved from one side 100 to the other throughout their lengths and longitudinally curved throughout their lengths recedingly from said opposed cooperating faces, said faces being recessed divergingly inward from the outer ends and from side to side thereof to form surfaces substantially straight transversely of said jaws and cutting edges extending from side to side of the respective jaws, whereby the edges of said opposed faces form rugged 105 pointed cutters and said faces serve to grip an object between them.

GEORGE G. MITCHELL.
